UNITED STATES PATENT OFFICE.

GEORGE ANTHONY AIKEN, OF CLIFTON, NEW JERSEY.

METHOD OF CUTTING SHIRTS.

1,378,164.

Specification of Letters Patent. Patented May 17, 1921.

Application filed April 13, 1920. Serial No. 373,679.

To all whom it may concern:

Be it known that I, GEORGE ANTHONY AIKEN, a citizen of the United States, residing at Clifton, in the county of Passaic and 5 State of New Jersey, have invented a new and useful Method of Cutting Shirts, of which the following is a specification.

This invention relates to the manufacture of shirts, and it is the object of the invention to provide a novel method of cutting shirts, to reduce the waste of material incident to the manufacture thereof, to a minimum.

A further object of the invention is to 15 provide a pattern changing the lower outline of a garment, whereby sections of a garment may be formed by a single operation, the pattern being arranged on the material under operation in a manner to facilitate 20 the cutting of the garment.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:—

The figure illustrates a plan view of a pattern constructed in accordance with the present invention.

Referring to the drawing in detail, the pattern is shown as including opposed pattern sections, each of which comprises a body 5 employed in forming both of the sides of a shirt, each of the body portions 35 being provided with a curved portion 6 forming one section of the neck of the shirt,

while the curved portion 7 disposed at the upper rear edge of the blank or body 5 forms one section of the sleeve opening.

The lower edge of the body is curved as at 45 8, there being provided a relatively straight portion 9 connecting the curved edge 8 and the front edge 10 of the body.

The forward edge of the blank is cut away as at 11, the cut away portion extending 50 from a point adjacent the upper end of the blank, terminating at a point in spaced relation with the lower edge 9 of the body to provide the usual extension 12.

In the application of a pattern of this 55 character, the upper portion of the figure illustrates the manner in which the pattern is placed on the material to be cut, while the lower portion of the figure discloses the manner of positioning a section in the succeeding step of the cutting operation, and from the foregoing it will be seen that the curved lower edges of the sections may be positioned to engage each other to reduce the waste of material in the manufacture of 60 65 shirts.

Having thus described the invention, what I claim as new is:—

A method of cutting shirts consisting in forming a pattern of a plurality of sections 70 having curved ends, positioning the curved ends of the pattern together and placing them on the material under operation, and finally cutting the cloth by the pattern.

In testimony that I claim the foregoing 75 as my own, I have hereto affixed my signature in the presence of two witnesses.

GEORGE ANTHONY AIKEN.

Witnesses:
